224,007

CHAIR

John W. Caldwell, 2202 Pinecrest Drive,
Altadena, Calif. 91001

Filed July 31, 1970, Ser. No. 24,255

Term of patent 14 years

Int. Cl. D6—02

U.S. Cl. D15—1

FIG. 1

FIG. 3

FIG. 4

FIG. 5

FIG. 1 is a side elevation of a chair according to the invention;

FIG. 2 is a cross-section taken at line 2—2 of FIG. 1;

FIG. 3 is a cross-section taken at line 3—3 of FIG. 1;

FIG. 4 is a longitudinal one-half view taken at the center line of symmetry (the other half being its mirror image), said view being taken at line 4—4 of FIG. 1; and

FIG. 5 is a front elevation of FIG. 1 showing the left half, taken on said center-line of symmetry, the other half being the mirror image.

I claim:

The ornamental design for a chair, as shown and described.
